UNITED STATES PATENT OFFICE

2,571,830

TELESCOPING PENCIL

Paul W. Buell, Elmira, N. Y., assignor to Point-O-Matic Pencil Co., Inc., Elmira, N. Y., a corporation of New York

Application January 2, 1948, Serial No. 6

1 Claim. (Cl. 120—14.9)

1

This invention relates to a pencil in which the lead is fed by the relative sliding movement between two telescoping barrel portions.

A particular object of the invention is to provide a pencil structure that will have a number of features of construction that will combine to produce a pencil that will operate under all circumstances, in which lead may be stored for use, and one in which the lead holding means is so constructed that the lead will be firmly and securely held to provide a fixed writing point down to the last small piece of lead being used in the writing operation.

A further object of the invention is to provide in a pencil structure of the character referred to a novel method of telescopically mounting the barrel portions of the pencil so that they have close sliding fit without marring the under barrel surface, will resist accidental telescoping action and will remain in perfect alignment at all times.

Still further objects of the invention provide for the close machining of the lead tube so that the lead may be properly held and fed, a simplified construction that is sturdy, will not get out of order, will not require skill in filling with lead or adjusting the parts preparatory to writing and one that can be made at minimum cost.

With these and other objects in view, the invention comprises certain constructions herein-after described and then particularly pointed out in the claim and a preferred embodiment of my invention is illustrated in the accompanying drawing, in which:

Figure 1 is a view in sectional elevation of a pencil constructed in accordance with my invention,

Figure 2 is a greatly enlarged fragmentary section in elevation of a part of the pencil where the barrels telescope showing a preferred form of structure,

Figure 3 is a section on the line 3—3 of Figure 2,

Figure 4 is a section on the line 4—4 of Figure 1 showing a modified form of barrel connecting means,

Figure 5 is a section taken on the line 5—5 of Figure 1 showing the relation of the barrel and lead tube,

Figure 6 is a vertical view of the pencil, parts being shown in section, illustrating the first movement of lead feed action, and

Figure 7 is a view similar to Figure 6 showing the completed movement of the lead feeding action, and

2

Figure 8 is a greatly enlarged sectional view of the lower end of the lead tube showing a modified form of construction thereof.

Referring to the drawing in detail, 10 indicates the upper barrel and 11 the lower barrel of an automatic pencil structure in which said upper and lower barrels are arranged for relative telescoping movement to progressively feed the lead at intervals as it is worn by the writing action. The upper barrel 10 of tubular construction and open at both ends is arranged at its lower end to closely fit over the upper end of the lower barrel 11, and is arranged to receive by friction fit a removable plug cup 12 in the upper end thereof. The cup 12 forms a closure at the upper end of the barrel in either position of use, that is to expose the eraser 13 therein or the closed end of said cup 12. The cup is positioned by the annular flange 14 which rests on the upper edge of the barrel. The barrel carries the usual clip 15 and in the interior adjacent the upper end of the barrel has force fitted therein a spring cup formed by providing a plug 16 with a central bore 17 or recess in which a coil spring 18 is lodged. The latter is held in the cup by a disk 19 which has a central opening for passage of the lead feed rod 20, the upper end of which is secured in any suitable manner to the end of the spring 18. The disk 19 may be frictionally retained in place in the cup or threaded therein as desired. In Figure 7, an adjustable plug 21 is threaded into the cup to close the spring recess and by adjusting this plug, the tension of the spring may be varied or adjusted to compensate in lead feeding action.

The lower barrel 11 at its upper end is closed by a tube plug 22 in which is mounted a lead guide tube 23 which extends through the barrel, passing through a guide disk 24 fixed near the lower end of the barrel, and also passing through the lower tapered end 25 of said barrel. The lead tube 23 is fixed in the disk 24. The plug 22 can be removed from the upper end of the tube 23 and the barrel 11 so that the space underneath may be used for lead storage as indicated as at 26. The upper end of barrel 11 near the extremity thereof is fluted outwardly as at 27 to provide elongated ridges which may be of any number as three or eight as shown to guide the upper barrel in its sliding movement over the lower barrel. A preferred form of structure is that illustrated in Figures 2 and 3 wherein the upper end of the barrel 11 is annularly fluted or grooved to provide a plurality of vertically spaced grooves 28 constituting seats for tension

rings 29 disposed in said grooves and arranged to frictionally engage the inner surface of the lower edge of the upper barrel 10. The rings 29 are normally tensioned to open to a larger circumference than the barrel 10 with the result that when they are put in place they hug the inner wall of the barrel and provide a floating connection between the barrels that insures their proper alignment at all times and, as in the case of the flutes, prevents the inside surface of the upper barrel from engaging and wearing the smoothly finished outer surface of the lower barrel, or marring the same.

The lower end of the lead guide tube 23 is slotted as at 30 and while actually shown of reduced diameter for the purpose of illustration, the machining of said tube will be such that its inside diameter will be .050 reduced to .047 near the point and to .046 at the tip to hold the lead tight enough to prevent it from falling out or turning. The slotted tip allows for variation in the size of the lead and the point of the barrel is just large enough to allow for this expansion.

In using the pencil, a writing lead is inserted through plug 22 into the lead tube 23 and the upper barrel 10 and a lead feed rod 20, are assembled with the lower barrel 11, with the feed rod extending into tube 23 to a point just above the lead in tube 23. Holding the pencil in vertical position, the user presses the point of the pencil against the writing material. The spring 18 is compressed as shown in Figure 6 by the movement of the feed rod and the resistance of the lead which is flush with the lower edge of the barrel 11. Compression of the spring is accompanied by a relative telescoping movement between the upper and lower barrels. Upon release of the pencil and the tension of the spring, the latter projects the lead to the position shown in Figure 7 and the pencil is ready for writing. The barrels maintain their position of adjustment as above noted, the rod holds the lead in position and prevents it from sliding back and the spring provides the right amount of tension to make the breaking of the lead an impossibility during writing even when excessive pressure is applied. The tension on the spring is adjustable as above noted and the gripping force of the lower end of the tube is just right to hold the lead so that it can be used down to about one thirty second of an inch in length so that loss of lead is minimized.

It is evident that while the slotting of the tube

as at 30 may be done only in the tip end thereof, said slots, as at 32 in Figure 8, may be made as long as desired and may extend into an enlarged part of the tube as shown.

5 Each time that the lead wears down it is simply necessary to apply telescoping pressure as above set forth with one hand to the upper barrel and then release the tension and the lead will have been advanced to provide a new writing supply that extends the correct amount beyond the end of the barrel.

10 My invention is not to be restricted to the precise details of construction shown since various changes and modifications therein may be made without departing from the scope of the invention or sacrificing the advantages to be derived from its use.

What I claim is:

15 A mechanical pencil comprising interfitting upper and lower detachable cylindrical barrels, one of said barrels being fluted to provide annularly spaced vertical ridges for frictional engagement with the other barrel to provide telescopic movement therebetween; a guide disk in the 20 lower barrel, a lead tube supported in said disk concentrically of the lower barrel and slotted at its lower end for frictionally holding lead, said lead tube extending substantially the length of said lower barrel to define with the barrel a storage space for leads above the guide disk, a 25 plug in the upper end of the lower barrel fitting about said lead tube and removable to provide access to said storage space, a recessed plug fixed in said upper barrel, a spring in the recess of the plug, a feed rod depending from said spring and extending into the lead tube above a lead disposed therein, and a disk closing the recess in said recessed plug and imprisoning said spring and said spring being compressible upon relative 30 telescopic movement of said barrels and expandable to project lead beyond the end of the lead tube through said feed rod.
